UNITED STATES PATENT OFFICE.

CLEON M. HANNAFORD, OF RICHMOND, VIRGINIA.

ANGLE-COCK HOLDER.

Application filed August 22, 1922. Serial No. 583,657.

To all whom it may concern:

Be it known that I, CLEON M. HANNAFORD, a citizen of the United States, residing at Richmond, in the county of Henrico 5 and State of Virginia, have invented a certain new and useful Improvement in Angle-Cock Holders, of which the following is a full, clear, and exact description.

The object of this invention is to provide 10 a holder for angle cocks, which may be readily applied, securely held in place, and serve to adequately support the train pipe, and be readily removed and at the same time prevent the angle cock from turning 15 and from pulling off from and pulling out the train pipe.

The invention consists of an angle cock holder, made in one piece and having a front portion which is divided to straddle 20 the angle cock between the hex and body of the angle cock and thus to engage the said angle cock and also having individual rearward extensions at the top of the front portion which are separate from one another and adapted to overlie and be engaged with a support fixed on the car above 25 the angle cock and the train pipe on which it is fixed, and also to engage the adjacent faces or angles of the hex of the angle cock, this holder being applicable to the angle 30 cock from below by an upward tilting movement in a rearward direction from in front of the hex on the angle cock, as I will proceed now to explain and finally claim.

35 In the accompanying drawings illustrating the invention, in the several figures of which like parts are similarly designated, Figure 1 is a side elevation showing the holder of the invention in the process of 40 application and also applied. Fig. 2 is a front elevation. Fig. 3 is a vertical section, of the holder detached, taken in the plane of line 3—3, Fig. 2. Fig. 4 is a cross-section taken in the plane of line 4—4, Fig. 1. Fig. 5 is a fragmentary side elevation illustrating a modified form of 45 holder; Fig. 6 is an elevation, and Fig. 7 is a vertical section of the same.

1 may represent a portion of an end sill 50 of a car, to which is fastened the support, here shown as an L-shaped metallic bracket 2 located at the point where the train pipe 3 passes outwardly from beneath the car. 4 is the hex and a small adjacent portion 55 of the ordinary angle cock screwed to the train pipe 3 as usual.

The holder 5 as shown in Figs. 1 to 4, may be described as an exaggerated unconventional V-shaped structure, having the front portion 6 extending from below the 60 angle cock upwardly in front of its hex.

As shown, the upper ends of the holder are extended backwardly or toward the car, as at 7, and these rearward extensions have downwardly projecting outside flanges 8 65 and the walls 9, the extensions 7 overlying the horizontal portion of the support 2 while the flanges 8 engage the edges of this support to thereby hold the holder in place on the support, and the walls 9 contact with 70 the upper faces or angles of the hex to prevent displacement as well as rotation of the angle cock.

It is obvious from the foregoing that the holder can not be applied to the angle cock 75 and support by a straight movement. It is necessary to effect the application to tilt the holder upwardly from beneath the angle cock as indicated by dotted lines 10 in Fig. 1, and then by a sort of turning movement 80 to bring the extensions 7 backwardly over the hex, as indicated by the dotted lines 11, and then by a further and final backward turning movement to properly position the holder on the support and in engagement 85 with the angle cock, as shown by the full lines.

The invention is susceptible of modifications within its principle, and without attempting to detail all of such modifications, 90 I have herein shown one in Figs. 5, 6 and 7. This modification differs from the construction already described in several particulars. For example, as shown in Fig. 6, the front contour may be segmental or U-shaped instead of V-shaped, and the front portion 6 95 may be strengthened or reinforced by a right-angled flange or rib 12, and the side flanges may be extended clear down to the rib, as indicated at 13. This holder is applied in a way similar to that first described.

In both constructions herein illustrated the rearward extensions are provided with bolt holes 14 through which extend the ends of the staple-like bolts 15, which straddle the pipe 3 and pass from beneath through the horizontal portion of the support 2, and are fastened down on top of the rearward extensions 7 by means of the nuts 16. Similar bolts, or even ordinary U-bolts 17, may be used to engage the pipe 3 and the hori- 105 110

zontal portion of the support 2 back of the holder, for securing the outward extension of the pipe 3.

These holders have their side elements spaced apart or divided and connected at the bottom, while their upper ends together with their rearward extensions are separate from one another or unconnected transversely. Thus the holder is adapted to straddle the angle cock between the hex and the body thereof, with the front portion arranged in front of the hex.

It will be understood of course that in order to detach or remove either of the holders, the bolts 15 are first removed and then the holder is tilted in a reverse direction from that used in applying it.

As will be observed, the constructions shown and described do not require the use 20 of a pocket in the holder for engaging the angle cock.

It is to be noted also that in both constructions the holder is of one piece.

As indicated, in both constructions, the 25 walls 9 are provided to engage at least and preferably two of the faces or angles of the hex. By locating these walls above the axis of the cock as shown, they not only prevent the cock from turning but also prevent it 30 from escaping vertically.

The use of the present A. R. A. standard type "D" coupler, so-called, requires an extension of the train pipe in order to properly place the train-pipe coupling arrangement, and it is desirable to support the thus-extended train-pipe in order that it and its attached angle-cock may not be dislocated. The support 2 affords means for the support of the extended train-pipe, in that its 40 horizontal portion may be made of any length required by such extension and the angle-cock holder rests upon its top and is bolted thereto by the bolts 15, the train-pipe being thereby drawn up into intimate supporting contact with the underside of the support and rigidly so held.

By removal of the nuts 16 the bolts are free to be disconnected from the support, angle-cock holder and train-pipe, and the 50 holder may then be detached. No other part of the mechanism need be disturbed.

The holders by reason of the simplicity of their design may be economically manufactured by drop-forging, so that they combine 55 great strength and lightness.

What I claim is:-

1. An angle cock holder, made in one piece and having a front portion divided to straddle the angle cock between the hex and body of the angle cock, and having 60 separate rearward extensions at the top of the front portion and integral therewith to engage a support fixed on the car and also having portions to engage the adjacent faces of the hex of the angle cock to prevent

the angle cock from turning, the holder being applicable to the angle cock from below by an upward tilting movement rearwardly from in front of the hex on the angle cock.

70

2. In an angle cock holding device, the combination with a support having a horizontal portion extending outwardly from the car, of a one piece holder having a longitudinally divided front portion to straddle the angle cock between the hex and body of the angle cock, a separate rearward extension at the top of each division of the front portion and overlying the horizontal portion of the support, said holder also having walls between the front portion and extensions engaging at least two faces of the hex of the angle cock, and means to rigidly connect the support, the holder and the angle cock.

80

3. In an angle cock holding device, the combination with a support having a horizontal portion extending outwardly from the car, of a one piece holder having a longitudinally divided front portion to straddle the angle cock between the hex and body of the angle cock, a separate rearward extension at the top of each division of the front portion and overlying the horizontal portion of the support, said holder also having walls between the front portion and extensions engaging at least two faces of the hex of the angle cock, side flanges on the extensions engaging the side edges of the support, and means to rigidly connect the support, the holder and the angle cock.

95

4. In an angle cock holding device, the combination with a support having a horizontal portion extending outwardly from the car and against the underside of which the train pipe bears directly, of a one piece holder having a longitudinally divided front portion to straddle the angle cock between the hex and body of the angle cock, a separate rearward extension at the top of each division of the front portion and overlying the horizontal portion of the support, said holder also having walls between the front portion and extensions engaging at least two faces of the hex of the angle cock, the holder being applicable to the angle cock by a tilting movement rearwardly from in front of the hex on the angle cock, and means to rigidly connect the support, the holder and the angle cock.

100

5. An angle cock holder, made in one piece, and having a front portion divided to straddle the angle cock between the hex and body of the angle cock and having separate rearward extensions at the top of the front portion to engage the hex and also to engage a support fixed on the car, and provided with downwardly extending outside flanges and inside walls, the latter serving to engage at least two of the faces of the

110

115

120

125

130

hex of the angle cock, said holder adapted to be applied by a rearward tilting movement from in front of the angle cock.

6. An angle cock holder, made in one piece and having a front portion divided to straddle the angle cock between the hex and body of the angle cock, and having separate rearward extensions at the top of the front portion and integral therewith to engage a support fixed on the car and also having portions to engage the adjacent faces of the hex of the angle cock to prevent the angle cock from turning, said holder having a reinforcing rib at the bottom of the front portion, the holder being applicable to the angle cock from below by an upward tilting movement rearwardly from in front of the hex on the angle cock.

7. An angle cock holder, made in one piece and having a front portion divided to straddle the angle cock between the hex and

body of the angle cock, and having separate rearward extensions at the top of the front portion and integral therewith to overlie a support fixed to the car, said holder provided with inside walls at its upper portion between its front portion and its rearward extensions to bear against opposite faces of the hex when in position and also having outside flanges extending downwardly from the rearward extensions to engage the lateral edges of the support, said holder applicable to the angle cock by a tilting movement rearwardly from in front of the angle cock.

In testimony whereof I have hereunto set my hand this 21st day of August, A. D. 1922.

CLEON M. HANNAFORD.
